UNITED STATES PATENT OFFICE.

FRED W. ZIEMENDORF, OF STEVENS POINT, WISCONSIN.

DRAFT-EQUALIZER.

1,146,297.

Specification of Letters Patent. Patented July 13, 1915.

Application filed April 16, 1914. Serial No. 832,277.

To all whom it may concern:

Be it known that I, FRED W. ZIEMENDORF, a citizen of the United States, residing at Stevens Point, in the county of Portage and State of Wisconsin, have invented certain new and useful Improvements in Draft-Equalizers; and I do hereby declare the following to be a full, clear, and exact description of the invention, such as will enable others skilled in the art to which it appertains to make and use the same.

This invention relates to new and useful improvements in draft equalizers and has particular reference to that type of such devices which are readily attachable to the evener bar of any vehicle.

As a particular object this invention contemplates the provision of an equalizing clevis which will be readily attachable to any vehicle or machine, and which will adjust the draft so that unequally mated animals will receive corresponding portions of the draft thereof on pulling the vehicle or machine.

An object of equal importance with the foregoing, is to provide an equalizing clevis of the type described, which is constructed with such regard to the arrangement of the parts as to be cheaply manufactured, will be durable and efficient in operation and may be readily applied to the evener bar and save considerable time and labor without requiring any alteration in construction of the latter.

The above objects are accomplished by such means as are illustrated in the accompanying drawing, described in the following specification and more particularly pointed out in the claims which are a part of this application.

Before taking up the description of the drawing, I desire to emphasize the fact that while my invention as designed with particular reference to the matter of road vehicles has been illustrated and will be described in that connection, it may be nevertheless applied with equal efficiency to a plow, cultivator, or any other type of similar machine.

By referring to the drawings wherein I have shown the preferred embodiment of my invention, similar characters of reference denote corresponding parts throughout the several views.

Figure 1 is a top plan view of an evener bar provided with my attachment and

shown in dotted lines in the position assumed by the element when unequally mated animals are pulling the vehicle. Fig. 2 is a bottom plan view of my attachment, the parts being shown in section, and, Fig. 3 is a transverse sectional view taken on the line 3—3 of Fig. 1.

Referring to the drawings, the numeral 5 designates the evener bar of the ordinary construction such as may be used upon any vehicle and provided adjacent its ends with the pivoted links 6 and 7 which pivotally connect swingletrees 8 and 9 of the usual construction thereto. To the forward face of this evener bar 5 and in the center thereof, I attach the semicylindrical bearing 10 which is made of any suitable material and has formed integrally therewith the lateral securing plates 11 and 12. These securing plates are provided with apertures 13 which are adapted to receive suitable securing means 14 whereby the bearing 10 is held in rigid relation with the evener bar adjacent the point where the said plates 11 and 12 are joined to the bearing 10, notches 11^a and 12^a are formed. The bearing 10 being more than a half circle the notches do not come in contact with the rounded end 16' when the evener bar 5 is in normal position.

The second main element of my invention is composed of the clevis 15 which embraces the bearing 10 and the evener bar 5 as is clearly shown in Fig. 3 and upon the latter of which it is transversely positioned. This clevis has its forward face rounded as shown at 16 to conform to the semicylindrical surface of the bearing 10 forming a concave bearing therefor upon which it is adapted to freely move, such rounded portion terminating oppositely in the shoulders 16' which serve to limit said free movement. Upon the rearward end of the clevis is formed the rearwardly extending bearing 17 which is integral therewith and which is provided with the vertical aperture 18 through which the hammer bolt of the vehicle is adapted to pass thereby pivoting the clevis to the vehicle.

It will be apparent from the foregoing description that should the driven animals engaged in pulling the vehicle be unevenly mated that I have provided a device capable of equalizing the draft of the vehicle so that the stronger or more capable animals will receive a large proportion thereof. If for instance the animal attached to the swing-

tree 9 is weaker or less capable than the animal attached to the swingletree 8, it will fall back into the position shown by the dotted lines in Fig. 1, this change of position of the 5 evener bar 5 will cause a change in the point of contact of the bearing 10 with the rounded end 16 of the clevis, and also a change in the line of draft through the clevis, from the said point of contact to the pivotal point 10 18. When the difference between the animals composing the team is sufficient to permit one of the notches 11^a or 12^a to come in contact with the end of the rounded portion 16' then the pull is in the notch which 15 is in contact and the line of draft is from that notch to point 18, as the slow horse moves up, the point of contact changes toward the center until when the team is pulling evenly the point of contact is in the 20 center of the rounded end, and the line of draft is the medial line of the clevis. Thus the point of draft is shifted automatically a distance equal to the width of the clevis. 25 It will also be apparent that this adjustment for apportioning the draft of the vehicle between the draft animals equal to their strength is entirely automatic and requires no operation whatever on the part of the driver. 30 A further advantage obtained by this construction is that if two equally mated animals are used with the vehicle provided with my invention and one of the animals is forced to proceed through a particularly 35 muddy spot of ground while the other animal is traversing firm ground, the unequal conditions under which they are working will be adjusted until the bad place in the road is passed. 40 While in the foregoing I have illustrated

in the drawing, and described in the specification the combination and arrangement of elements that constitute the preferred embodiment of my invention I desire to emphasize the fact that I may make such minor 45 changes and alterations which will not depart from the spirit of the invention nor conflict with the scope of the appended claims.

What I claim is:—

1. A draft equalizer comprising a semi-cylindrical bearing, having laterally extending securing plates and notches adjacent said bearing, in said plates; an equalizer bar, means for securing said bearing to said bar; a clevis embracing said bar and having a concave bearing seat in the forward end thereof adapted to receive said bearing, and means to pivotally attach said clevis to a vehicle. 50

2. The combination with an evener bar and a semi-cylindrical bearing secured to said bar, of an equalizing clevis, a rounded portion formed at one extremity of said clevis, an apertured extension formed at the 55 other extremity of said clevis to receive the hammer bolt of the vehicle, and shoulders formed at the extremities of said rounded portion by providing a passage through said clevis for the reception of said bar and said bearing so that the latter is rotatably embraced by said rounded portion. 60

In testimony whereof I have signed my name to this specification in the presence of two subscribing witnesses.

FRED W. ZIEMENDORF.
